UNITED STATES PATENT OFFICE.

GEORGE E. GUY, OF TOTTENVILLE, NEW YORK

ROTARY PISTON-PUMP.

1,250,860.

Specification of Letters Patent. Patented Dec. 18, 1917.

Application filed November 26, 1915. Serial No. 83,597.

To all whom it may concern:

Be it known that I, GEORGE E. GUY, residing at Tottenville, in the county of Richmond and State of New York, citizen of the 5 United States, have invented or discovered certain new and useful Improvements in Rotary Piston-Pumps, of which improvements the following is a specification.

The object of my invention is to provide 10 a rotary piston pump, which will be simple and practical in the construction and arrangement of its parts, and efficient in operation.

In the accompanying sheet of drawings 15 I have illustrated the preferred embodiment of my invention. Figure 1 is a side elevation of the pump; Fig. 2 a horizontal sectional view taken on the line II—II, Fig. 1; Fig. 3 a vertical sectional view 20 taken on the broken line III—III, Fig. 2; and Fig. 4 a cross-sectional view taken on the line IV—IV, Fig. 1.

In the pump which I provide there is an outer casing provided with intake and discharge chambers and orifices, and with passageways affording a minimum resistance to the flow of fluid to and from such chambers. To the central portion of the casing there is fixedly secured a multiple 30 throw shaft, on one axis of which there is rotatably mounted a drum, provided with a plurality of radially arranged cylinders. On a second axis of such shaft a sleeve or equivalent member is rotatably mounted, such sleeve having pivotally connected to it 35 suitable pistons adapted to reciprocate within the drum cylinders to draw fluid into and discharge it from such cylinders. Depending upon the intended capacity of 40 the pump, the number and arrangement of the cylinders and pistons will vary. In the pump shown herein two sets of cylinders and pistons are provided, the sets of pistons rotating on axes disposed on opposite 45 sides of the axis of rotation of the cylinder drum, the arrangement being such that during the operation of the pump there will be a balance of the internal forces. Provision is made within the casing 50 to cause the fluid to act upon the opposite ends of the drum, thus preventing such end thrusts as would otherwise cause undue wear of the parts and inefficient operation

of the pump. Finally, the connections for driving the drum are such as to relieve the 55 driving shaft from lateral strain and the prejudicial effects attending it.

Referring to the embodiment of the invention illustrated in the drawings, the casing comprises a substantially cylindrical shell 1 and end plates 2 and 3, the shell 1 being provided with a laterally extending base portion 4. Before describing the arrangement and formation of fluid chambers and passageways within the casing, I will 60 explain the internal construction of the pump. The end plate 2 is provided with a cylindrical block 5 having an eccentric longitudinal bore adapted to receive and firmly hold an end 6 of a multiple-throw 65 shaft 6, 6^a, 7. This shaft, as will be readily observed, is suitably provided with lubrication ducts leading to the several bearing portions thereof. The axis of the central section 7 of said shaft coincides with the 70 center or axis of the cylindrical casing 1, and the axes of the adjoining sections are parallel with, and lie on opposite sides of, that of the central section, as clearly shown in Figs. 2 and 4.

80 Rotatably mounted on the shaft section 7 is a drum 8 provided with two sets of radially arranged cylinders 9 and 9^a; while on the shaft sections 6 and 6^a there are rotatable sleeves 10 and 10^a, respectively. To 85 the sleeve 10 there are pivotally connected, through links or rods 11, pistons 12, corresponding in number to the cylinders 9, and adapted to reciprocate in such cylinders, and in the same manner the sleeve 10^a 90 is connected to pistons 12^a. To the end that each sleeve may, without binding or other prejudicial effect, rotate upon its respective axis or shaft section, simultaneously with the rotation of the drum 8 upon the 95 shaft section 7, such sleeves are operatively connected to the drum, as by links 13 and 13^a, respectively.

As thus far explained, it will be readily understood that the rotation of the 100 drum 8 will cause corresponding rotation of the sleeves and consequent reciprocations of the pistons within the cylinders. The preferred means for rotating the drum will be presently described. The casing member 1 is provided, on opposite sides of a

plane including the axes of the shaft sections 6, 6^a, 7, with substantially crescent shaped intake and discharge chambers. As shown particularly in Fig. 3, there is an 5 intake chamber 14 in the upper and a discharge chamber 15 in the lower portion of the casing 1 adjacent to the cylinders 9, and an intake chamber 14^a in the lower and a discharge chamber 15^a in the upper 10 portion of such casing adjacent to the cylinders 9^a. Between the intake and discharge chambers 14 and 15, the casing, as seen in Fig. 4, bows inwardly to meet the drum 8, thus forming chamber separators 15 16 and 17 of widths greater than the diameter of the cylinders 9. In a similar manner the chambers 14^a and 15^a are likewise divided by separators 16^a and 17^a. An inlet orifice 18 communicates directly with the 20 intake chamber 14^a, and an outlet orifice 19 with the discharge chamber 15. Finally, the intake chambers 14 and 14^a are connected with each other and with the inlet orifice 18 by means of a spiral passageway 20, formed in one side of the casing 1, and the 25 discharge chambers 15 and 15^a are connected with each other and with the outlet orifice 19 by a spiral passageway 21 on the other side of the casing.

30 To the ends of the drum 8 there are secured, in any suitable manner, plates 22 and 23. The plate 22 is provided with a boss 24 which is rotatably mounted on the block 5, the axis of such block coinciding with that of the shaft section 7. The plate 23 is also provided with a boss 25, to which a driving shaft 26 is suitably secured. That such shaft may not, when driven, be subject to lateral strain, it is preferably driven by a 40 bell or dog 27, keyed or otherwise secured to the shaft, and rotatably mounted, through ball bearings 28, upon a laterally extending boss 29 of the casing end-plate 3. As will be understood, the bell 27 may be driven by a 45 belt, shaft, or any other suitable driven connection.

As already stated, provision is made to cause the fluid to act on the opposite ends of the drum to prevent an unbalanced thrust 50 thereof. For this purpose, I preferably so shape the end casing plates 2 and 3 as to form, with the drum plates 22 and 23, end annular chambers 30 and 31. The fluid from either the intake or discharge chambers may 55 be let into such end balance chambers, and this either through such slight space as there must necessarily be between the end casing plates 2 and 3 and the adjacent drum plates 22 and 23, or suitable by-passes 32 and 33 60 may, as shown in Fig. 3, be formed in the plates 2 and 3 and the shell 1.

The operation of the pump is as follows: The driving shaft 26 is rotated to cause the drum 8 to revolve in a left hand direction as 65 viewed in Fig. 4. Considering the set of

70 pistons and cylinders shown in such figure, the pistons 12 will, as they move from the right to the left of the intake chamber 14, be moved inwardly and thereby draw fluid into their respective cylinders 9. At the extreme left position, each piston is at its maximum inward position, and in such position the cylinder is closed by the separator 16 as such cylinder is moved from the intake to the discharge chamber. When moving 75 from left to right, the pistons gradually move outwardly and thus discharge the fluid from their respective cylinders to the discharge chamber. In precisely the same manner, although with a reverse arrangement 80 of intake and discharge chambers, the pistons 12^a operate within the cylinders 9^a.

85 As is readily apparent, the drum 8, and the sleeves 10 and 10^a with their connected pistons, each rotate simultaneously on their respective axes, so that there is no unbalanced centrifugal action on the multiple throw shaft. Furthermore, the intake and discharge chambers for each set of pistons and cylinders are disposed on opposite sides 90 of the pump so that the internal forces of the fluid are balanced. Also, the arrangement of fluid chambers and conduits is such that there is a continuous flow of the fluid with a minimum resistance thereto.

95 According to the provision of the patent statutes, I have described the principle and operation of my invention, together with the mechanism which I now consider to represent the best embodiment of my invention. 100 However, I desire to have it understood that the mechanism shown is only illustrative, and that the invention may be practised by other means.

1. I claim as my invention:

105 1. In a rotary piston pump, the combination of a casing, having a cylindrical inner wall, a shaft secured thereto against rotation and having a central section with an axis coincident with that of said inner wall and 110 having adjoining end sections with axes eccentric to and on opposite sides of said central section, a drum rotatably mounted on said central shaft section and provided with two sets of radially arranged cylinders, 115 sleeves rotatably mounted on said end shaft sections, sets of pistons reciprocatory in said cylinders and having link connection with said sleeves, and means for rotating said drum, said casing being provided with inlet 120 and outlet orifices and with an intake and discharge chamber on opposite sides of each of said sets of cylinders.

125 2. In a rotary piston pump, the combination of a rotary drum provided with a plurality of radially arranged cylinders open at their outer ends, a sleeve rotatable on an axis eccentric to that of said drum, pistons reciprocatory in said cylinders and having link connections to said sleeve, a casing sur-

rounding the drum and provided on opposite sides thereof with intake and discharge chambers, a rotatable driving shaft secured to said drum and projecting through the 5 casing, and a driving member rotatably mounted on said casing and connected to said shaft.

In testimony whereof I have hereunto set my hand.

GEORGE E. GUY.
